UNITED STATES PATENT OFFICE.

EDMOND MARTIN, OF POTSDAM, NEW YORK.

SPRAY-NOZZLE.

SPECIFICATION forming part of Letters Patent No. 699,801, dated May 13, 1902.

Application filed August 16, 1901; Serial No. 72,298. (No model.)

To all whom it may concern:

Be it known that I, EDMOND MARTIN, a citizen of the United States, residing at Potsdam, in the county of St. Lawrence and State of New York, have invented a new and useful Spray-Nozzle, of which the following is a specification.

This invention relates to nozzles, and has for its object to provide an improved device of this character particularly designed for use as a lawn-sprinkler and is arranged to conveniently secure a plurality of adjustments for varying the character of the discharge—as, for instance, to secure a fine spray and also a broad projected sheet of water in the nature of a fountain.

It is, furthermore, designed to provide for conveniently controlling the direction of discharge, so that the water may be discharged laterally in any direction and cut off in the opposite direction, which feature of the invention is designed to obviate the wetting of a walk or the side of a building by directing the discharge of water laterally away from such parts, so as to effectually sprinkle the adjacent portions of the ground.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view illustrating the present form of nozzle applied as a lawn-sprinkler. Fig. 2 is a detail perspective view of a nozzle embodying the present invention. Fig. 3 is a central longitudinal sectional view thereof. Fig. 4 is a similar view showing the adjustable cut-off sleeve in position to close one side of the nozzle. Fig. 5 is a detail perspective view of the adjustable cut-off sleeve.

Like numerals of reference designate corresponding parts in all of the figures of the drawings.

Upon reference to the accompanying drawings it will be seen that the present device

embodies an open-ended tubular body 1, which has one end provided with an enlarged internally-screw-threaded portion 2 to form a coupling for connection with a hose or other water-pipe in the common or ordinary manner. Within the interior of this body there is provided a transverse diametric cross-bar or bridge 4, which is comparatively narrow, so as not to materially obstruct the passage of water through the nozzle and having a screw-threaded opening formed at the center of the bar designed for the adjustable reception of the screw-threaded stem 5 of the baffle or sprayer plate 6, that is located outwardly from what will be termed the "outer" end of the nozzle and of greater diameter than the latter, so that it may be set tightly against the adjacent end of the body, and thereby effectually close the nozzle. For convenience in adjusting this plate there is provided one or more projections or finger-pieces 7 upon the outer side of the plate, whereby the latter may be rotated to feed the stem 5 in an endwise direction through the opening in the supporting cross-bar 4. The inner face of the sprayer-plate is provided with a concentric groove or seat 8, which lies outwardly of the body 1.

It will be understood that when the plate 6 is set snugly against the adjacent end of the tubular body the latter is closed against the passage of water, and by rotating the plate it may be adjusted or extended outwardly from the body, and thereby provide a marginal opening between the latter and the plate and for the lateral discharge of water radially in all directions. By varying the distance between the sprayer-plate and the tubular body either a very fine spray discharge or a comparatively broad discharge may be secured, the latter discharge being in the nature of a fountain.

Upon the exterior of the tubular body there is provided a rotatable and endwise slidably adjusting-sleeve 9, which is slightly shorter than the body, and is limited in one direction in its endwise movement by the marginal stop-shoulder 10, formed by the enlarged coupling portion of the body, and in its opposite direction by the marginal edge portion of the sprayer-plate 6, that projects laterally beyond the body. A portion of the outer

edge of the sleeve is cut away so as to provide the substantially semitubular flange portion 11, that is designed to be projected beyond the outer end of the tubular body and 5 into the marginal groove or seat in the inner face of the sprayer-plate, as clearly indicated in Fig. 4 of the drawings, thereby closing one-half of the marginal opening between the sprayer-plate and the nozzle-body, while the 10 opposite half of said opening is unobstructed to permit of the free lateral discharge of water. It will be understood that the interior of the adjustable sleeve and the exterior of the body are smooth and have a comparatively 15 snug frictional engagement, so that the sleeve is retained thereby at any desired adjustment. A frictional engagement of this character is preferable, as it permits of a quick adjustment of the sleeve and is sufficient to 20 hold the latter, as there is no strain thereon. For convenience in adjusting the sleeve the exterior of the latter is roughened to afford a finger-grasp portion, preferably by providing the same with a plurality of marginal 25 grooves 12.

By means of the adjustable sleeve 9, which is constructed to cut off the lateral discharge in one direction, while permitting of the discharge in the opposite direction, the nozzle 30 or sprinkler may be located adjacent to a walk or building, with the cut-off-flange portion 11 disposed toward the walk or building to cut off the discharge of water in that direction, thereby obviating wetting of the walk 35 or building while the water is being directed to sprinkle portions of the ground adjacent to the walk or building.

It will be understood that this form of nozzle directs the water laterally and is therefore 40 designed for application to a stiff upright pipe-section, as indicated in Fig. 1 of the drawings, rather than to an ordinary flexible hose. Should the nozzle be applied to a hose, it will be necessary to employ a suitable 45 holder for supporting the nozzle in an upright position.

By reference to the sectional views 3 and 4 it will be observed that the cut-off flange 11 when received within the marginal seat or 50 groove 8 in the sprayer-plate 6 forms a watertight joint therewith, and by reason of the slidable mounting of this sleeve the latter may be simultaneously moved inwardly with the sprayer-plate when the latter is rotated 55 to move the same inwardly, whereby the sleeve does not interfere with the inward adjustment of the sprayer device and also does not require to be adjusted independently thereof.

60 What I claim is—

1. In a nozzle, the combination with a tubular body, and a sprayer device at one end thereof, of a cut-off sleeve mounted upon the body in co-operative relation to the sprayer 65 device, and having means for directing the discharge laterally at one side only of the sleeve, also having an endwise-slidable ad-

justment and a rotatable adjustment, the two adjustments being independent of each other.

2. A nozzle, comprising a tubular open- 70 ended body, a sprayer device adjustable toward and away from the outer end of the body, and an endwise-movable cut-off sleeve mounted to slide freely upon the body into and out of engagement with the sprayer, and 75 provided with means for directing the discharge laterally at one side only of the sleeve, the latter also being capable of an inward movement under the influence of the inward adjustment of the sprayer device. 80

3. A nozzle, having a cut-off sleeve provided with means for directing the discharge laterally at one side only thereof, and also having a rotatable adjustment, and an endwise-slid- 85 able adjustment, said adjustments being entirely independent of each other.

4. A nozzle having a sprayer device at one end, and a cut-off sleeve having an endwise- 90 shiftable adjustment into and out of engagement with the sprayer device, and provided at its outer end with a lateral discharge-opening, the sleeve also having a rotatable adjustment which is independent of its endwise adjustment.

5. A nozzle, comprising a tubular body hav- 95 ing a smooth exterior, and provided at one end with a sprayer device, and an endwise-movable cut-off sleeve having means to direct the discharge at one side thereof, a smooth interior embracing the body and slidable to- 100 ward and away from the sprayer device, and a frictional engagement with the body to hold the sleeve against accidental endwise movement.

6. A nozzle, comprising a body, a sprayer 105 device which is adjustable toward and away from one end thereof, and an endwise-adjustable cut-off sleeve slidably embracing the body and provided at its outer end with a partly-cylindrical cut-off flange for coöperation 110 with the sprayer device, whereby the discharge may be directed at one side only of the nozzle and the width of the discharge-opening may be varied.

7. A nozzle, having a sprayer device which 115 is adjustable toward and away from one end thereof, said device being projected outwardly beyond the body and having the inner face of the projected portion provided with a marginal seat, and an endwise-adjustable cut-off 120 sleeve mounted upon the body and provided with a partly-cylindrical flange for directing the discharge laterally at one side thereof, the outer end of the flange being adapted to fit in the marginal seat of the sprayer device, 125 said sleeve also having a rotatable adjustment which is independent of its endwise adjustment.

8. A nozzle, comprising a tubular body, a sprayer device located externally at one end 130 of the body and projected marginally beyond the same, the inner face of the projected portion thereof having a marginal groove formed therein, and an endwise-adjustable cut-off

sleeve mounted upon the body and having its outer end provided with a longitudinally-projected cut-off flange to be received within the groove of the sprayer.

- 5 9. A nozzle, comprising an open-ended tubular body having its inner end provided with a coupling, and an internal cross-bar having a screw-threaded opening, a sprayer-plate located externally at the outer end of the body 10 and projected marginally beyond the same, the inner face of the projected portion of the plate having a marginal groove, a central screw-threaded stem carried by the plate and adjustably received within the opening in the 15 cross-bar, and a cut-off sleeve mounted upon the body for independent endwise and rotatable adjusting movements thereon, and provided at its outer end with a semicylindrical cut-off flange in coöperative relation to the 20 groove in the sprayer-plate.

10. A nozzle, having a cut-off sleeve which is provided with means for directing the discharge laterally at one side only thereof, and also has an endwise-shiftable adjustment and 25 a rotatable adjustment, said adjustments being entirely independent of each other and also capable of simultaneous action.

11. A nozzle, comprising a tubular body having a smooth exterior, and provided at 30 one end with a sprayer device, and a cut-off sleeve having means to direct the discharge at one side only thereof, and also capable of an endwise-slidable adjustment, and a rotatable adjustment which is independent of the 35 endwise adjustment, the interior of the sleeve being smooth and embracing the body with a frictional engagement to hold the sleeve against accidental movement thereon.

12. A nozzle, comprising a tubular body,

the outer end of which is entirely open, a sprayer device which is normally out of engagement with the outer end of the body, whereby the discharge may be in all directions from the body as a center, and a cut-off sleeve embracing the body and having its outer end provided with a partly-cylindrical flange for engagement with the sprayer to direct the discharge at one side only, said sleeve having an endwise adjustment to bring the flange into engagement with the sprayer device and also to withdraw the flange inwardly beyond the outer edge of the body, and also provided with a rotatable adjustment which is independent of the endwise adjustment to vary the direction of the lateral discharge.

13. A nozzle, comprising a tubular body, a sprayer device located externally thereof and adjustable toward and away from one end of the body to direct the discharge laterally in all directions from the nozzle as a center, and an endwise-adjustable cut-off sleeve having one end provided with a partly-cylindrical cut-off flange for engagement with the sprayer device to direct the discharge laterally in one direction only, said sleeve also having a rotatable adjustment which is independent of its endwise adjustment, whereby the direction of discharge may be varied and the size of the discharge-opening may be adjusted.

In testimony that I claim the foregoing as my own I have hereto affixed my signature in the presence of two witnesses.

EDMOND MARTIN.
